UNITED STATES PATENT OFFICE

JOSEPH C. WOODMAN, OF FLUSHING, NEW YORK, ASSIGNOR TO DECARIE INCINERATOR CORPORATION, OF NEW YORK, N. Y., A CORPORATION OF NEW YORK

SCREENINGS BURNER

Application filed May 23, 1929. Serial No. 365,378.

This invention relates to dehydrating incinerators and has for its principal object the disposal of wet sewage screenings or sludge in a clean and efficient manner.

The sludge may be obtained from the sewer by any suitable process. Usually it is dripping wet and in such a dense and mucky condition that it will not readily burn, and hence it must be drained or dried before it is possible to incinerate it. By the use of an incinerator such as disclosed in this invention, the sludge may be dumped therein just as it is extracted from the sewer, whereupon it will be dehydrated and burned. The incinerator herein described is also well adapted to receive dried screenings or such material in any condition in which it may be obtained. Garbage and other refuse will also be readily consumed as well as practically any other combustible material.

The above objects of this invention are accomplished by a novel disposition of material treating portions of the incinerator, which may include grates in combination with oil burners to dry the sludge and ignite it. At least one of the grates may be used for coal firing to augment the oil burners or to substitute for them at times when they may be out of operation. Other of the grates may be of water tube structure combined with a water jacketed furnace wall providing a durable heat resisting structure which is adapted for use as a steam generating chamber so that the incinerator becomes a source of both heat and power which may be used for any desired purpose. Forced draft and preheating means may be employed, and any suitable methods of coal, gas, or oil firing are intended to be used. A drain leading back to the sewer is located at the bottom of the ash pit to provide for an excess of water which may be dumped in with the sludge and which may not be transformed into steam to pass out the flue. A booster burner is used which insures sufficient temperature in a gas combustion chamber through which the gaseous products of combustion pass, thus reducing smoke to a minimum, and substantially eliminating odor.

The particular nature of the invention as well as other objects and advantages thereof will appear more clearly from a detailed description of a preferred embodiment as illustrated in the accompanying drawings in which

Fig. 1 is a sectional longitudinal elevation thru the center of the incinerator;

Fig. 2 is a sectional end view taken along the line 2-2 of Fig. 1, and

Fig. 3 is a plan view taken along the section 3-3 of Fig. 1.

Referring to the drawings, a chute 1 provided with a trap door 2 is built into the floor or platform 3 such that trucks may be driven up and dumped near the chute, or into the chute directly. Any other suitable means of conveying material to the chute may be employed. The chute 1 leads into the incinerator 4, passing through an opening in the boiler or steam generating chamber 5 which forms the sides and top of a combustion chamber 4a. Directly under the chute 1 is a drying grate 6 forming a platform, located at a distance below such that a suitable depth of material may be deposited thereon. This grate is composed of parallel water tubes individually terminating at each end in a reducing point 7, the rear ends of the tubes being connected thereby to a supporting header 8 which spans the combustion chamber 4a and connects with the water-jacketed walls 5a of the incinerator at the points 9 in Fig. 2. The forward ends of these tubes 6 are connected by the reducing joints 7 to tubes 10, which pass through sleeves in the front water-jacketed wall of the incinerator and connect with the header 11 by means of the T's 12. This header extends along the front of the incinerator and around each end to connect with the water-jacketed side walls 5a of the incinerator at the points 13 in Fig. 3. The tubes are so connected as to be readily cleaned.

Below the grate 6 is a second grate comprising the bars 14 supported at the ends by cross-members which are supported at the lower part of the furnace wall. This grate is adapted to burn coal as well as any refuse which may drop through the drying grate

above. Coal is supplied through the opening 15 in the front water-jacketed incinerator wall 5a which is closed by the doors 16. The space below this grate comprises an ash pit 17 to which access may be had through the doors 18. At the bottom of the pit is a drain 20 to carry off liquids to the sewer. At each side of the drying grate 6 is provided an oil burner 25, one above and one below, (Fig. 2), the purpose of which is to dry out the wet sludge that is deposited on the grate 6 and to accelerate the combustion throughout the chamber. Water dripping from this sludge which is not evaporated will be drained out from the bottom of the ash pit through the drain 20. The purpose of the coal fire is to augment the operation of the oil burners, but it may be operated alone under conditions wherein the oil burners are not needed or may be dispensed with entirely when the hydrocarbon burners are adequate for the treatment of the sludge or refuse.

As the sludge dries on the upper grate 6 it is stoked through a door opening 27 that is normally closed by doors 28, and is pushed off onto an intermediate grate 26, where, if all the moisture has not been removed from it, the sludge becomes thoroughly dried and will begin to burn. The material is pushed off the upper grate 6 by any suitable tool, the operation being facilitated by the parallel and longitudinal disposition of the grate members. The intermediate grate 26 comprises the water tubes 26a the rear tube being somewhat raised above the plane of the grate to prevent material dropping over the rear. The tubes extend across the combustion chamber and are connected at one end directly to the water-jacket of the wall 5a of the incinerator, and the other ends of the tubes pass through sleeves in the wall of the furnace at the opposite side of the incinerator and are fitted with T-sections 29, an outlet of each T-section being connected with tubing 30 that with suitable fittings leads back to the water-jacketed side wall 5a as shown in Fig. 2. This construction allows the tubes 26 to be cleaned as the T-sections are closed by removable plugs aligned with the bores of the tubes 26. This grate may be observed and raked through the openings 31 in the incinerator side walls 5a, which openings are closed by doors 32.

A fourth or bottom grate 35 is located directly beneath the intermediate grate 26 and to the rear of and below the coal grate 14. This grate is similar in construction to grate 14, but the bars are arranged perpendicular to those of the latter and parallel to the tubes of the intermediate grate above. Both grates 35 and 14 are adapted to be shaken. The arrangement is such that partly burned or unburned material may be transferred from either of these grates onto the other. The gap between them is bridged for this purpose

by an inclined surface 36 placed above a cross wall 37 which separates the ash pit 17 from the pit 38 under the rear grate 35. This grate is accessible through the doors 39 in the side of the incinerator, and the ash pit 38 is reached through doors 40. The front and rear walls 41 of the ash pits 17 and 38 are shown as being I-beams that support the front and rear water-jacketed walls of the combustion chamber of the furnace structure. The side water-jacketed walls are likewise supported by these I-beams. The whole metallic structure of the incinerator is placed on a concrete base 42.

The gaseous products pass out of the furnace chamber 4a through the opening 43 in the rear water-jacketed wall 5a and into a gas combustion chamber 50 lined with refractory material 51, and provided with a baffle wall 52, the chamber being accessible through the doors 53. An auxiliary oil burner 54 is placed near the entrance of this chamber and is adapted to build up the temperature to insure the reduction of all odors and the complete combustion of any smoke or other floating material which might be stirred up by the draft in the combustion chamber. In this manner the amount of soot is reduced to a minimum and very little smoke is emitted from the stack, so that the plant operates in the cleanest possible manner and with no odor that would otherwise offend neighboring habitations.

An air preheater 55 is placed in the chamber 50, which is comprised of lateral rectangular ducts 56 through which the flue gases pass, and vertical rectangular ducts 57 carrying a forced draft that is supplied to the preheater through a conduit 61 leading from a fan 62 driven by a motor 63, downwardly to a conduit 58. This conduit leads to the bottom of both grates 14 and 35. The amount of draft supplied to either grate may be regulated by the dampers 59 placed in the conduit at its entrance to the spaces beneath the grates.

The flue gas is conducted from the preheater 55 through the outlet passage 64 which may be partially or completely closed by a damper 65. This damper is controlled by means of a cable or chain 66 passing over a pulley 67.

It will be understood that various changes may be made in the arrangement of the preferred embodiment herein described without departing from the principles of the invention as defined in the appended claims.

I claim:

1. In an incinerator, the combination with a combustion chamber having a plurality of air inlets and a gas outlet, of horizontal refuse supporting means comprising a preliminary treating section and a combustion section, drying means proximate to said preliminary treating section and combustion means below

- said combustion section, said sections being vertically spaced apart and the combustion section being located between the preliminary treating section and the gas outlet, the end portion of said combustion section proximate to the gas outlet being slightly raised to prevent the refuse on said section from being carried out through the gas outlet and the other end portion underlying a portion of the preliminary treating section to prevent the refuse transferred from the preliminary treating section to the combustion section from falling directly onto the combustion means beneath the preliminary treating section. 70
- 5 2. An incinerator comprising a steam generating chamber, a plurality of water tube drying grates connecting therewith and arranged for transfer of material from one to another, heating and igniting means associated with the grates, another grate arranged to receive material from said drying grates, a separately fired grate, and a transfer surface extending between the latter grates. 75
- 10 3. In an incinerator, enclosing structure forming a combustion chamber having a plurality of air inlets and a gas outlet, refuse supporting means in said chamber comprising an initial grate for holding the refuse for preliminary treatment and a combustion grate, said grates being substantially in parallelism and vertically spaced apart, the combustion grate extending under the initial grate and toward the gas outlet, fuel burning means above and below said initial grate, and refuse-catching and fuel burning means disposed under said initial grate below the plane of said combustion grate, whereby the refuse on said grates of the supporting means is subjected to an elevated temperature from above and below said supporting means. 80
- 15 4. In an incinerator, structure forming a combustion chamber provided with separate ash pits and having air inlets to the respective ash pits and a gas outlet, air-regulating means for the individual air inlets, refuse supporting means in said chamber comprising a substantially horizontal initial grate for holding refuse for preliminary treatment and a substantially horizontal combustion grate below and extending under said initial grate and toward the gas outlet, drying means above and below said initial grate, and other combustion grates over the individual ash pits and vertically under said initial grate and first named combustion grate respectively. 85
- 20 5. In an incinerator, the combination with a combustion chamber having air inlet means and a gas outlet, of refuse supporting means comprising a preliminary treating section and a combustion section, and fuel burning means positioned above and below the preliminary treating section of said refuse supporting means, said combustion section being supported below said preliminary treating section and being arranged to extend thereunder and into proximity to the gas outlet so that the hot gases from the fuel burning means pass above and below the combustion section on their way to the gas outlet. 90
- 25 6. In an incinerator, the combination with a combustion chamber having an air inlet means and a gas outlet, of a refuse supporting means comprising a horizontal preliminary treating section and a horizontal combustion section, said sections being located in different horizontal planes and being displaced one from the other to permit the transfer of refuse from the preliminary treating section to the combustion section, the arrangement of the sections being such that substantially all of the liquid material draining from the preliminary treating section will fall clear of the combustion section, and fuel burning means above and below the preliminary treating section, said combustion section being so located relative to the gas outlet that the heated gases from the fuel burning means will pass above and below it on their way to the gas outlet means. 95
- 30 7. In an incinerator, a combustion chamber having a gas outlet, a refuse supporting means in said chamber comprising a preliminary treating section and a combustion section, said sections being in different horizontal planes and displaced horizontally one from the other, fuel burning means correlated to said preliminary section, said combustion section being located in the path of the hot gases flowing from the fuel burning means to the gas outlet, structure forming a hot gas passageway communicating through said gas outlet with the combustion chamber, an air preheater in said passageway, said preheater having an atmospheric air inlet and a heated air outlet, a conduit connected to the heated air outlet of said preheater and opening into the combustion chamber proximate to said fuel burning means to supply heated air thereto, and a second conduit connected to said first conduit and opening into the combustion chamber proximate to said combustion section for supplying heated air to said section. 100
- 35 8. In an incinerator comprising a water-jacketed combustion chamber having a gas outlet, a receiving grate formed of a plurality of parallelly supported tubular members in communication with the water jacket, fuel burning means adjacent said receiving grate, a second grate disposed in a different horizontal plane at one side of said receiving grate and between said fuel burning means and the gas outlet, said second grate being formed of a plurality of tubular members 105 in communication with the water-jacket and angularly disposed relative to the tubular members of the receiving grate, and a fuel burning grate beneath said first grate and in a plane below that of said second grate. 110
- 40 9. In an incinerator comprising a water-jacketed combustion chamber having a gas outlet, a receiving grate formed of a plurality of parallelly supported tubular members in communication with the water jacket, fuel burning means adjacent said receiving grate, a second grate disposed in a different horizontal plane at one side of said receiving grate and between said fuel burning means and the gas outlet, said second grate being formed of a plurality of tubular members 115 in communication with the water-jacket and angularly disposed relative to the tubular members of the receiving grate, and a fuel burning grate beneath said first grate and in a plane below that of said second grate. 120
- 45 10. In an incinerator comprising a water-jacketed combustion chamber having a gas outlet, a receiving grate formed of a plurality of parallelly supported tubular members in communication with the water jacket, fuel burning means adjacent said receiving grate, a second grate disposed in a different horizontal plane at one side of said receiving grate and between said fuel burning means and the gas outlet, said second grate being formed of a plurality of tubular members 125 in communication with the water-jacket and angularly disposed relative to the tubular members of the receiving grate, and a fuel burning grate beneath said first grate and in a plane below that of said second grate. 130
